STABILIZED KLYSTRON

George D. O'Neill, Port Washington, and Leo C. Eisaman, Flushing, N. Y., assignors to Sylvania Electric Products Inc., a corporation of Massachusetts

Application May 1, 1948, Serial No. 24,546

3 Claims. (Cl. 315—5)

1

The present invention relates to electron discharge devices, and more particularly to electron discharge devices of the velocity modulation type employing a hollow resonator and in which a stream of electrons from a cathode is passed through a gap in said resonator and is reflected back through the gap by a reflecting electrode. Such devices are commonly known as reflex klystron tubes. In the operation of such devices as generators of high frequency oscillations, a condition has been encountered which made it appear that two sets of operation were possible with any given tube, resulting in two sets of reflector mode characteristics which were approximately parallel to each other, and were separated by 50 to 100 volts on the reflector voltage characteristic.

These sets of operation were such that the power output of each was approximately the same and the tube appeared to operate equally well in either condition. It was, however, impossible to control or predict which of these conditions the tube would choose to operate under, and frequently the tube would jump from one condition to the other during operation. This alternative operating effect may be called "mode jumping." Thus, the tube may operate in a number of distinct and mutually exclusive modes in which the number of the mode is designated N , such that $N = fT$ where f is the resonant frequency and T is the time an electron spends in the drift space; that is, the space between the resonator grid and reflector. Also, $N = (n - \frac{1}{4})$ where n is an integer greater than 0 and the time T depends upon the field in the drift space. If all other charged bodies are far removed, T depends upon the reflector voltage, specifically,

$$T = \frac{4x}{V} \left(\frac{e_b}{e_b - e_r} \right)$$

where x is the grid-reflector spacing, V is the electron velocity at the grid, e_b is the grid voltage and e_r is the reflector voltage.

Now, in the tubes in which this condition was observed, the envelope of the tube was made of insulating material, such as glass, at least in the area between the final resonator electrode and the seal-in point of the reflector electrode. It has been deduced that this mode jumping is indirectly caused by electrons from the cathode of the tube passing through the resonator grids and being scattered by the mesh of the grids. As a result of the scattering some of the electrons strike the glass wall of the tube envelope between the resonator electrode and the reflector elec-

2

trode. The electrons striking the glass wall may cause one of two effects; that is, either a negative charge is built up on the glass wall, or the electrons striking the glass wall cause a secondary emission which in turn results in a change in space charge in the reflector field. A study of the potential gradient between the final resonator electrode and the reflector electrode by means of an electrolytic plotting tank indicated that either of the effects stated above would result in a distortion of the reflector field to an extent that mode jumping would occur.

An object, therefore, of the present invention is to provide an arrangement for stabilizing the retarding field between the resonator grid and the reflector electrode of a reflex klystron.

Another object of the present invention is the provision of means for stabilizing the mode of operation of a reflex electron beam oscillator.

Still another object of the present invention is the improvement of the stability of operation of a reflex klystron.

Still a further object of the present invention is the provision of an improved means for providing a conductive coating on the interior wall of a glass envelope and the connection between the conductive coating and a lead-in terminal sealed in the glass wall of the tube.

In accordance with an aspect of the present invention, the building up of a charge on the glass envelope may be prevented by providing a thin metallic coating on the interior wall of the envelope in conductive connection with the lead through terminal associated with the reflector electrode. The coating is preferably spaced a distance of the order of one thirty-second of an inch from the final resonator electrode.

As a further aspect of the present invention, it is contemplated that an improved contact may be obtained between the conductive coating and the reflector electrode lead by mounting a getter strip on the reflector electrode lead in such a way that, as the getter is flashed, a conductive coating will be established between the reflector electrode lead and the conductive coating within the tube envelope.

Alternatively, the conductive coating within the glass envelope may be in the form of a thin aluminum coating evaporated onto the interior surface of the tube envelope prior to assembly of the tube.

The present invention will be more fully understood by reference to the following detailed description which is accompanied by a drawing in which

Fig. 1 illustrates in partial longitudinal cross-

section a tube embodying the principles of the present invention, while

Fig. 2 is a graph illustrating the potential gradient along a line between the resonator grid and the reflector electrode of the tube in Fig. 1, while

Fig. 3 is an enlarged fragmentary longitudinal cross-section of the tube of Fig. 1 with the equi-potential contour lines in the space between the resonator grid and reflector electrode plotted for two conditions of operation.

In Fig. 1 of the drawing, reference numeral 10 indicates the evacuated glass envelope of an electron discharge device having at one end a cathode structure 12. The cathode structure 12 incorporates a heated electron emissive surface and focusing means for projecting a beam of electrons through grid 13 in apertured electrode 14, and further, through grid 15 in apertured electrode 16. Electrodes 14 and 16 are in the form of conductive metal discs passing through the wall of the glass envelope 10 of the tube.

Preferably, electrodes 14 and 16 terminate in cylindrical rims 18 and 20 adapted to make good contact with the walls of an exterior resonating chamber. The resonating chamber is not shown since it may be of various forms and of varying dimensions, depending upon the desired frequency of operation of this system.

The stream of electrons from cathode 12, after passing through grids 13 and 15, is reflected back through the resonator gap between grids 13 and 15 by a suitable negative potential applied to reflector electrode 22. The energizing potentials on the electrodes of the tube are so related to the dimensions of the tube and the associated resonating chamber as to cause the reflected electrons to pass back through the gap between electrodes 13 and 15 in bunches, thus exciting the associated resonant cavity into oscillation.

In the tube, as so far described, and without the provision of some special means of preventing such action, electrons may so far fail to be influenced by the reflector electrode 22 as to pass between the edges of the reflector electrode 22 and the electrode 16 and strike the glass wall of the envelope 10. Alternatively, they may be scattered by a diffracting action of the wires constituting grid 15. The electrons striking the inner glass wall of envelope 10 cause a charge to be built up on said wall, which can only slowly be dissipated due to the high resistance of the glass surface. When a sufficient charge has been accumulated on the interior surface of the glass envelope 10, the shape of the field between the resonator grid 15 and the reflector electrode 22 may be so far influenced or redistributed, that the tube will fail to continue to oscillate in its original mode, or if the tube does continue to oscillate in its original mode when the tube is turned off and then again turned on, it may begin to oscillate in a different mode, dependent upon the new voltage distribution. However, we have found that if the interior wall of glass envelope 10 is coated with a thin conductive coating of metal, such as aluminum evaporated onto the interior surface, and if this coating is connected to the lead for reflector electrode 22 by some suitable means, the potential gradient between reflector electrode 22 and resonator grid 15 is maintained at a constant value, so that, no matter how many times the tube is turned on and off, it always oscillates in the same mode of operation.

We have found that a convenient way for assuring good electrical contact between the lead

for reflector electrode 22 and the conductive coating 30, is to so mount the getter strip 32 on the reflector electrode lead that, as the getter is flashed, the material from the getter is deposited on the seal between the reflector electrode lead and the conductive coating 30, thus assuring a continuous conductive path between the coating 30 and the reflector lead. Contact between these two conductive elements may also be established by a conductive cat's whisker attached to the reflector electrode and contacting the conductive coating.

In Fig. 2 we have plotted the potential gradient between the resonator grid 15 and the reflector electrode 22. In this family of curves, voltages are plotted as ordinates against distances along a line between grid and reflector electrodes as abscissae. In this diagram, curve 50 illustrates the variation of potential from the reflector electrode to the resonator grid under the condition when no current is flowing through the tube. It is apparent that the voltage distribution follows a straight line in this case. Now, if current is drawn through the tube, the potential distribution between the reflector electrode and resonator grid changes to that shown by curve 51. As a voltage is built up on the interior of the glass wall of the envelope, the potential distribution may change to that shown by curve 52. A mode of operation may then be possible with the field represented by this curve. The distance indicated by the double headed arrow A indicates the amount of readjustment of electrode potentials that is necessary in order to assure operation in the same mode as along line 51. Now it has been found that if a conductive coating is applied to the interior of the glass envelope, operation is stabilized along the curve 53 of Fig. 2. It will be noted that this line follows very closely the line 51 so that no substantial change in operating mode is encountered as the tube continues to operate. Further, each time the tube is turned on again it operates in the same mode as before.

In Fig. 3 we have shown in greatly enlarged detail the upper portion of the tube of Fig. 1 with the equi-potential contour lines plotted in the space between the reflector electrode 22 and the resonator grid 15. The location of the conductive coating and the connection between that coating and the lead-in wire for electrode 22 is also more apparent in this figure.

The solid line curves 60 in Fig. 3 illustrate potential contour lines determined by the use of an electrolytic plotting tank for the condition where a conductive coating is present on the interior of the envelope while dotted contour lines 61 indicate potential contour lines for the condition where the conductive coating is not present. It should be noted that the dotted contour lines terminate at different points along the glass envelope of the tube. If the potential of the glass varies, the termination points of the contour lines may shift over the surface of the envelope, thus permitting a general reformation of the field within the space between grid 15 and electrode 22. In the case where the tube envelope is provided with a conductive coating, all contour lines terminate within a very narrow band, the limits of which are fixed by the lower edge of the conductive coating. Thus, there can be substantially no shifting of the potential distribution and no mode jumping is encountered.

While we have described a particular embodiment of the present invention for purposes of illustration, it will be understood that various

modifications and adaptations thereof may be made within the spirit of the invention.

What is claimed is:

1. A reflex klystron having an evacuated envelope of insulating material containing an electrode for providing a stream of electrons, first and second apertured disc electrodes interposed in the path of said stream, a reflector electrode towards which said stream is to be directed, said reflector electrode being substantially symmetrical with and disposed substantially transverse to the path of said electrons, a first conductive coating on the inside of said envelope extending to a point adjacent said second apertured disc electrode, and a second coating of conductive getter material overlying said first coating and in electrical contact with said first coating and said reflector electrode.
  2. A reflex klystron having an envelope containing an electron source electrode and an electron reflector electrode, a pair of cavity resonator electrodes passing through said envelope and positioned between said source electrode and said reflector electrode, and a continuous conductive coating on the interior wall of said envelope and in electrical contact with said reflector electrode, said coating extending from a region adjacent said resonator electrodes to a region on the side of said reflector electrode away from said resonator electrodes.
  3. A reflex klystron including an electron source electrode and a reflector electrode, said electrodes being mounted in an evacuated insu-

lating envelope, a pair of apertured cavity resonator electrodes passing through said envelope and positioned between said source electrode and said reflector electrode, said reflector electrode being separated by a space from the next adjacent cavity resonator electrode, and a shield connected to said reflector electrode and covering said envelope, said shield extending from a point adjacent said next adjacent cavity resonator electrode in said space between said cavity resonator electrode and said reflector electrode to a point on the side of said reflector electrode away from said next adjacent cavity resonator electrode.
